UNITED STATES PATENT OFFICE.

LOUIS N. TONNS, OF COLLEGEPOINT, NEW YORK, ASSIGNOR OF ONE-HALF TO EDWARD H. HALL, OF MOUNT VERNON, NEW YORK.

ENGINE.

SPECIFICATION forming part of Letters Patent No. 789,300, dated May 9, 1905.

Application filed July 12, 1900. Renewed September 23, 1904. Serial No. 225,569.

To all whom it may concern:

Be it known that I, LOUIS N. TONNS, a citizen of the United States, residing at Collegepoint, in the county of Queens and State of New York, have invented certain new and useful Improvements in Engines, of which the following is a specification.

My invention relates to engines, and particularly to that class of engines which have a rotary piston operated upon by an expandable gas.

I will describe an engine embodying my invention and then point out the novel features thereof in the claims.

15 In the accompanying drawings, Figure 1 is a cross-sectional view of an engine embodying my invention, taken on the line *a b* of Fig. 2, the said section being irregular in order that some parts may be shown in elevation. Fig. 2 is a cross-sectional view taken on the line *c d* of Fig. 1.

Similar letters of reference designate corresponding parts in both of the figures.

A represents a suitable casing having, preferably, an open central portion. For convenience it is made in two sections *a a'*, which are bolted together, and the lower section is provided with a base *a²*. Mounted on the base are two standards *a³*, provided with suitable bearings in which the ends of a shaft *B* are journaled. The shaft *B* is provided with a fly, balance, or other wheel *b*.

C represents a rotary piston which is keyed in position on the shaft *B*. The piston is here shown as being in the form of a pulley, the peripheral portion of which fits in and rotates in an annular recess or chamber provided in the casing. The periphery of the piston is provided with a channel, recess, or chamber *c*, which extends nearly around the periphery, so as to leave a portion *c'* against which the gas expands.

The upper portion of the casing *A* is provided with a chamber *d*, in which a swinging abutment *D* fits and works. The abutment *D* is keyed onto a shaft *d'* and is provided with the arms or projecting portions *d² d³*. The shaft *d'* is suitably journaled in the casing *A* and provided with a handle *d⁴*, by

means of which the abutment may be manually operated. If desired, the abutment *D* may be operated from the shaft *B*, and any suitable connection may be provided. The abutment *D* has a free movement in the chamber in order that it can be shifted by the incoming gas. The arms or projections *d² d³* are also of such a thickness as to close the channel, recess, or chamber *c* in the piston, so that the gas will not be permitted to expand except against the part *c'* of the piston.

d⁵ represents a chamber or recess in one side of the abutment through which the exhaust-gas passes. The chamber *d⁵* is in communication with a passage *d⁷*, provided in the casing *A*, with which recess an exhaust-pipe *d⁶* communicates.

E represents a part surmounting the casing *A* and secured thereto, in which is provided the gas-inlet passage *e*, which is branched to form the two passages *e' e²*, leading to opposite sides of the abutment *D*. A plug-valve *F* is provided in the part *E* and is provided with two ports or passages *f' f²*. The plug is adapted to be reciprocated by hand, and its movement in one direction is limited by a head *f³* and in the other direction by a pin *f⁴*. At the limit of the movement of the valve *F* in one direction one of the ports or passages—as, for example, *f'*—is in registry with the branch passage *e'* and at the limit of its movement in the opposite direction the port or passage *f²* is in registry with the branch passage *e²*. When the port *f* and passage *e'* are in registry, the piston will be driven in one direction, and when the port *f²* and passage *e²* are in registry the piston will be driven in the reverse direction.

G represents a cut-off valve for controlling the passage *e*. This valve is operated from the shaft *B* by means of an eccentric *g* and pitman *g'*. The valve may be of any desired form. I have shown it as being in the form of a rod having a reduced part *g²*, which portion is brought into the passage *e* when a charge of gas is to be expanded against the portion *c'*.

The gas preferably employed in the operation of this engine is carbonic gas. This may

be stored in tanks, which are connected with the passage e . As the gas enters the passage e it will pass to either side of the abutment D, according to which passage e' or e^2 the valve F has open. The gas contacting with the end of the abutment D rocks it on its shaft and escapes past it into the casing A and expands against the portion c' , thereby causing the piston to rotate. As the piston 10 rotates the part c' moves under the abutment and comes into position to have the next charge of gas to expand against it. The incoming charge of gas will force the abutment D down should it by any chance be held in 15 an elevated position.

In starting the engine in either direction the abutment is moved by the handle d^4 , though this is not absolutely necessary, its position being controlled mainly by the gas 20 entering either of the passages e' or e^2 . Also for a quick reversal of the engine the abutment may be operated by hand.

What I claim as new, and desire to secure by letters Patent, is—

25 1. In an engine, the combination of a casting, a rotatable piston within the casing and having a single channel extending nearly around its periphery, a chamber provided above the piston, a swinging abutment 30 mounted on a shaft and located in said chamber and adapted to have its ends fit in the channel of the piston for guiding an expandible gas or other power into said channel, branch passages for the power leading to said 35 abutment, a valve for controlling said passages, and a single exhaust - chamber provided in a side of the abutment between its ends which is in communication with the peripheral channel of the piston.

2. In an engine, the combination of a casting having a chamber, a rotatable piston located within said chamber and having a channel extending nearly around its periphery, a second chamber above the piston-chamber, a swinging abutment located in said second chamber and adapted to have its ends fit in the channel of the piston, a single exhaust-chamber provided in a side of the abutment between its ends which is in constant communication with the channel in the piston, 45 an exhaust-passage in communication with the exhaust-chamber, a passage for power which passage has branches for supplying power to either side of the abutment, and a valve for controlling said passages. 50

3. In an engine, the combination of a casting having a chamber, a rotatable piston located within said chamber and having a passage extending nearly around its periphery, a second chamber above the piston-chamber, 55 a swinging abutment located in said second chamber and adapted to have its ends fit in the channel of the piston, an exhaust-chamber provided in a side of the abutment and normally in communication with the channel 60 in the piston, a passage for power which passage has branches for supplying power to either side of the abutment, a valve for controlling said passages, and a second valve operated by an eccentric moving with the piston for intermittently cutting off the power. 65

In testimony whereof I have signed my name to this specification in the presence of two subscribing witnesses.
